US0D1006990S

(12) **United States Design Patent** (10) Patent No.: **US D1,006,990 S**
(45) Date of Patent: ** Dec. 5, 2023

(54) **TOOL HANDLE**(71) Applicant: **Medtronic, Inc.**, Minneapolis, MN (US)(72) Inventors: **Matthew T. Vanderpool**, Minneapolis, MN (US); **Michael R. Klardie**, Bloomington, MN (US); **Kris A. Peterson**, St. Louis Park, MN (US)(73) Assignee: **Medtronic, Inc.**, Minneapolis, MN (US)(**) Term: **15 Years**(21) Appl. No.: **29/748,593**(22) Filed: **Aug. 31, 2020****Related U.S. Application Data**

(63) Continuation of application No. 15/610,076, filed on May 31, 2017, now Pat. No. 10,786,279, which is a continuation of application No. 14/204,227, filed on Mar. 11, 2014, now Pat. No. 11,311,312.

(60) Provisional application No. 61/788,940, filed on Mar. 15, 2013.

(51) LOC (14) Cl. **24-02**

(52) U.S. Cl.

USPC ..... **D24/133**(58) **Field of Classification Search**

CLAIM

The ornamental design for a tool handle, as shown and described.

DESCRIPTION

FIG. 1 is a front perspective view of a tool handle according to a first embodiment of the present design;
FIG. 2 is front elevation view of the tool handle of FIG. 1;
FIG. 3 is a rear elevation view of the tool handle of FIG. 1;
FIG. 4 is a left side view of the tool handle of FIG. 1;
FIG. 5 is a right side view of the tool handle of FIG. 1;
FIG. 6 is a top plan view of the tool handle of FIG. 1;
FIG. 7 is a bottom plan view of the tool handle of FIG. 1;
FIG. 8 is a cross-sectional view of the tool handle of FIG. 1 taken in the plane of and the direction indicated by line 8-8 of FIG. 2, with a cross-sectional view taken in the plane of and in an opposite direction indicated by line 8-8 being a mirror image thereof;

FIG. 9 is a cross-sectional view of the tool handle of FIG. 1 taken in the plane of and the direction indicated by line 9-9 of FIG. 2;

FIG. 10 is a cross-sectional view of the tool handle of FIG. 1 taken in the plane of and the direction indicated by line 10-10 of FIG. 2;

FIG. 11 is a front perspective view of a tool handle according to a second embodiment of the present design;

FIG. 12 is front elevation view of the tool handle of FIG. 11;
FIG. 13 is a rear elevation view of the tool handle of FIG. 11;

FIG. 14 is a left side view of the tool handle of FIG. 11;
FIG. 15 is a right side view of the tool handle of FIG. 11;
FIG. 16 is a top plan view of the tool handle of FIG. 11;
FIG. 17 is a bottom plan view of the tool handle of FIG. 11;
FIG. 18 is a cross-sectional view of the tool handle of FIG. 11 taken in the plane of and the direction indicated by line 18-18 of FIG. 12, with a cross-sectional view taken in the plane of and in an opposite direction indicated by line 18-18 being a mirror image thereof;

FIG. 19 is a cross-sectional view of the tool handle of FIG. 11 taken in the plane of and the direction indicated by line 19-19 of FIG. 12; and,

FIG. 20 is a cross-sectional view of the tool handle of FIG. 11 taken in the plane of and the direction indicated by line 20-20 of FIG. 12.

The broken lines in the drawings are for the purpose of illustrating portions of the tool handle that form no part of the claimed design. Surfaces forming part of the claimed design are defined by shaded surfaces.
